UNITED STATES PATENT OFFICE.

WALTER T. BOBO, OF BATTLE CREEK, MICHIGAN, ASSIGNOR TO THE EASY TRUSS COMPANY, OF BATTLE CREEK, MICHIGAN.

TRUSS.

1,182,341.

Specification of Letters Patent. Patented May 9, 1916.

Application filed May 3, 1915. Serial No. 25,523.

To all whom it may concern:

Be it known that I, WALTER T. BOBO, a citizen of the United States, residing at Battle Creek, in the county of Calhoun and State of Michigan, have invented certain new and useful Improvements in Trusses, of which the following is a specification.

This invention relates to improvements in trusses.

10 The main objects of this invention are to provide in a truss an improved elastic belt and one in which the elastic portions are very strong and do not deteriorate in use, and further, one in which the main body 15 of the belt is non-elastic, and the elastic portion is confined to a small area adjacent the pad.

Further objects, and objects relating to structural details will definitely appear 20 from the detailed description to follow.

I accomplish the objects of my invention by the devices and means described in the following specification.

The invention is clearly defined and 25 pointed out in the claims.

A structure which is a preferred embodiment of my invention is clearly illustrated in the accompanying drawing forming a part of this specification, in which:

30 Figure I is a front perspective view of a truss embodying the features of my invention. Fig. II is an enlarged detail front elevation, the housing for one of the spring devices being broken away to show the arrangement of the parts. Fig. III is a detail longitudinal section on a line corresponding to line 3—3 of Fig. II. Fig. IV is an enlarged detailed section corresponding to that of Fig. III, showing structural 35 details.

In the drawings, similar reference characters refer to similar parts throughout the several views.

Referring to the drawings, the pad 1 is 45 preferably that of the Miller Patent No. 1,133,815, issued March 20, 1915. As its structural details form no part of this invention they are not further described herein.

50 A back piece 2 preferably of relatively stiff material is secured to the back of the pad by the screw 3 which is arranged through the rear wall of the pad and

threaded into a retaining plate 4 arranged therein. The body belt 5 is formed of non- 55 elastic material.

On the rear of the back piece 2 I arrange an elastic strap 6, the strap being secured by the clip plate 7 which is retained by the screw 3. The clip engages the strap 6 centrally so that both ends are free. Sets of coiled springs 8 are provided, the springs being provided with cross bars 9 at their inner ends and cross bars 10 at their outer ends. The cross bars are provided with 65 lugs 11 upon which the end coils of the springs are threaded or otherwise secured. The cross bars 9 are provided with key-hole slots 12 adapted to engage the screw 3 which is provided with a stud portion 13, 70 the screw having a collar-like enlargement 14 engaging the clip, there being sufficient space between this collar and the head of the screw to constitute an attaching stud for the cross bars 9. One of the cross bars 9 is 75 provided with a spring tongue 15 arranged over the slot and adapted to engage the stud, as shown in Figs. II, III and IV. The outer cross bars 10 are provided with belt connecting buckles 16, the buckles being pivotally 80 connected to the cross bars at 17.

The elastic strap 6 is secured to the outer cross bars at 10 by means of the studs 18. The strap 6 is preferably provided with a series of openings 19 adapted to receive the 85 studs 18 so that the elastic strap may be adjusted.

Loop-like housings 20 for the spring connections are provided. These housings are carried by the back piece. The strap 6 and 90 the springs and the connections therefor are entirely free from these housings so as to move freely therein.

The springs are so arranged that they do not come in contact with the body of the 95 wearer. The elastic strap is also protected, but should it deteriorate and become ineffective it may be renewed. The coiled spring connection is quite satisfactory without the elastic straps, but I prefer the combination as I have illustrated and described. 100

The elastic or resilient portion or connection of the belt is provided in a small area and is very effective and durable in use.

The drop strap 21 is provided with a belt 105 engaging loop 22 at one end and with a clip

23 engaging the stud 24 on the clip 7 at the other end.

Having thus described my invention, what I claim as new and desire to secure by Letters Patent, is:

1. In a truss, the combination of a pad, a back piece projecting at each side of the pad, an elastic strap arranged on the rear side of said back piece, a securing clip engaging the strap centrally, a pad attaching screw arranged through said back piece and securing the said parts together and constituting a belt attaching stud, a belt, sets of coiled springs, cross bars at each end of said sets of springs having lugs engaging the end coils of said springs, the inner cross bars being provided with keyhole slots engaging said stud, the outer cross-bars being provided with pivoted belt connecting buckles, the ends of the elastic straps being adjustably connected to said outer cross bars, and loop-like housings for said sets of springs carried by said back piece.
2. In a truss, the combination of a pad, a back piece projecting at each side of the pad, an elastic strap arranged on the rear side of said back piece, a securing clip engaging the strap centrally, a pad attaching screw arranged through said back piece and securing the said parts together and constituting a belt attaching stud, a belt, sets of coiled springs, cross bars at each end of said sets of springs having lugs engaging the end coils of said spring, the inner cross bars being provided with keyhole slots engaging said stud, the outer cross-bars being provided with pivoted belt connecting buckles, the ends of the elastic straps being adjustably connected to said outer cross bars.
3. In a truss, the combination of a pad, a back piece projecting at each side of the pad, a pad attaching screw constituting a belt attaching stud, a belt, sets of coiled springs, cross bars at each end of said sets of springs, having lugs engaging the end coils of said springs, the inner cross bars being provided with keyhole slots engaging said stud, the outer cross-bars being provided with belt connecting buckles, and loop-like housings for said sets of springs carried by said back piece.
4. In a truss, the combination of a pad, a back piece projecting at each side of the pad, a pad attaching screw constituting a belt attaching stud, a belt, sets of coiled springs, cross bars at each end of said sets of springs having lugs engaging the end coils of said springs, the inner cross bars being provided with keyhole slots engaging said stud, the

outer cross-bars being provided with belt connecting buckles.

5. In a truss, the combination of a pad, a back piece projecting at each side of the pad, an elastic belt centrally connected to said back piece, a belt, sets of coiled springs, cross bars at the ends of said springs to which they are connected, the inner cross bars being provided with belt connecting buckles, said elastic strap being connected to the outer cross bars, and loop-like housings for said sets of springs carried by said back piece.

6. In a truss, the combination of a pad, a back piece projecting at each side of the pad, a belt, sets of coiled springs, cross bars at the ends of said springs to which they are connected, the inner cross bars being connected to said pad, the outer crossbars being provided with belt connecting buckles, and loop-like housings for said sets of springs carried by said back piece.

7. In a truss, the combination of a pad, a back piece projecting at each side of the pad, an elastic belt centrally connected to said back piece, a belt, sets of coiled springs, disposed on the outer side of said back piece, cross bars at the ends of said springs to which they are connected, the inner cross bars being connected to said pad, the outer cross bars being provided with belt connecting buckles, said elastic strap being connected to the outer cross bars.

8. In a truss, the combination of a pad, a back piece projecting at each side of the pad, a belt, sets of coiled springs, disposed on the outer side of said back piece, and cross bars at the end of said springs to which they are connected, the inner cross bars being connected to said pad, the outer cross bars being provided with belt connecting buckles.

9. In a truss, the combination of a pad, a back piece projecting at each side of the pad, a belt, a belt attaching stud on said pad, a set of coiled springs, disposed on the outer side of said back piece, and cross bars at each end of said springs having lugs engaging the end coils of said springs, the inner cross bar being provided with a keyhole slot engaging said stud and the outer cross bar being provided with a belt connecting buckle.

In witness whereof I have hereunto set my hand and seal in the presence of two witnesses.

WALTER T. BOBO. [L.S.]
